UNITED STATES PATENT OFFICE.

FREDERICK A. SCHROEDER, OF ROCHELLE PARK, NEW JERSEY, ASSIGNOR TO RAYMOND CONCRETE PILE COMPANY, OF NEW YORK, N. Y., A CORPORATION OF NEW JERSEY.

CORRUGATING MACHINE.

Application filed May 20, 1926. Serial No. 110,342.

This invention comprises improvements in machines for corrugating sheet-metal pipes or shells, especially tapered shells such as are used in the construction of concrete 5 piles.

In the concrete pile art it is customary to mount a shell, usually formed of sheet steel, on a collapsible core, drive the core and shell into the ground, withdraw the 10 core, and fill the shell with concrete to form the finished pile.

The shell is simply a convenience in building the pile; it is of no importance in the finished pile, and usually rots away in 15 time, therefore it is desirable to make the shell of as thin material as possible in order to save cost.

However, the shell must be stiff enough to resist the crushing force of the surrounding earth or water after the core has been 20 withdrawn and before the shell has been filled with concrete.

To meet the divergent requirements of lightness of material and stiffness, it has 25 become customary to reinforce the shells with interior wires, or with interior spirally wound wires partially embedded in corrugations in the shell, or to corrugate the shells in such manner as to be independent of 30 wire reinforcements. The corrugations are spiral or helical, in order that different sections of shell may be readily joined together by screwing their ends together. This invention pertains to a machine 35 designed to corrugate shells of the last mentioned type.

In some of its features the machine is similar to the construction disclosed in Patent No. 1,155,389, issued October 5, 1915, to 40 Wainwright et al, which covers a "machine for manufacturing spirally reinforced pile shells".

An object of the present invention is to provide an improved method of driving the 45 various parts of the machine.

Another object is to provide improved methods of manipulating and adjusting the operative mechanisms in order to insure more positive and more rapid operation.

Another object is to provide the machine 50 with duplicate corrugating devices on opposite sides of the shell, thereby increasing speed of operation and thereby balancing side thrusts on the shell and its mandrel.

Further and other objects and advantages 55 will be hereinafter set forth in the accompanying specification and claims, and shown in the drawings, which by way of illustration show what is now considered to be the preferred embodiment of the invention. 60

Fig. 1 is a front view of the machine, partly in section and showing a partially corrugated shell in position.

Fig. 2 is a side view of Fig. 1, partly in 65 section.

Fig. 3 is an enlarged front view of the shell, mandrel, chuck and corrugating devices, partly in section.

Fig. 4 is an enlarged sectional view on 70 line 4-4 of Fig. 1.

Fig. 5 is an enlarged sectional view on the line 5-5 of Fig. 6.

Fig. 6 is an enlarged plan view of the top 75 of the machine.

Fig. 7 is a view of the corrugating wheel and its controlling devices looking in the direction indicated by the line 7-7 in Fig. 3.

Fig. 8 is a side view of Fig. 7.

Fig. 9 is a plan view, partly in section, of 80 Fig. 7.

Fig. 10 is a section on line 10-10 of Fig. 3.

The frame of the machine comprises principally a hollow base 10, and a head 12 supported from the base on a pair of columns 14. Extending from base to head are two members 16 which serve as sliding ways for the two corrugating devices which are 85 designated generally as 18.

Mounted for rotation in base 10 is the hollow vertical shaft 20, on the upper end of which is carried the chuck 22 upon which is mounted the collapsible mandrel 24, the upper end of which is guided for rotation 95 by devices supported by member 26 which in turn is supported on head 12. Mandrel 24 is screw threaded or corrugated in accordance with the corrugations desired in the shell.

Power is supplied to the machine through shaft 28, supported for rotation by bearings 30 in base 10. Fast on the inner end of shaft 28 is a bevel pinion 32 which drives the bevel gear 34, fast on shaft 20, thus rotating chuck 22 and mandrel 24. Fast to shaft 20 above gear 34 is another bevel gear 36 which drives horizontal shafts 38 by 105

means of pinions 40. Shafts 38 are supported for rotation by bearings 42 and 44 on base 10, and serve to drive, in a manner which will appear, the vertical feed screws 46, one of which is contained within each guide member 16.

For convenience of illustration mandrel 24 is shown in cylindrical form, and members 16 are vertical, but the machine finds 10 its greatest use in corrugating shells which are not cylindrical but tapered. The machine is required to handle shells of different diameters, and of different tapers, therefore the vertical members 16 are settable to a 15 great variety of positions, in all of which positions the feed screws 46 must be driven. This is accomplished as follows.

Each screw 46 is mounted for rotation in one of the guide members 16, suitable thrust 20 bearings 48 being provided to carry the load of screw and its corrugating device 18. The lower end of each screw is provided with a bevel pinion 50 in mesh with a bevel pinion 52 on shaft 54 in bearing 56 (Figs. 1 and 25 4). Bearing 56 is integral with member 60. Member 16 is pivotally supported at 57 by two semi-circular bearings and at 58 on a frame 60 which is slidably mounted on ways 62 formed on the upper surface of base 10.

30 If it be desired to incline member 16 to correspond to a tapered shell, bolts 64 (Fig. 1), which clamp the lower end of member 16 to frame 60, and bolts 66, which clamp the upper end of frame 16 to head 12, are 35 loosened, screw 68 is turned to rotate member 16 about its pivots 58 and 57 until the desired position of member 16 is attained, whereupon bolts 64 and 66 are tightened and the adjustment is complete.

40 The center line of pivots 58 coincides with the center line of shaft 54, therefore the above adjustment does not interfere with the proper engagement of pinions 50 and 52.

Pinion 52 is driven from shaft 38 by pinion 70, the hub 72 of which is splined on shaft 38 and supported for rotation by bearing 74 integral with frame 60. Normally, frame 60 is clamped to base 10 by bolts 76, but whenever it is to be moved, bolts 76 and 50 66 are loosened and screws 78 and 68 are turned with wrenches until the desired setting is reached, whereupon bolts 76 and 66 are re-tightened. It will be readily understood from the above description that the 55 driving and setting means are so designed that vertical frames 16 may be readily set to any desired position and taper, and that none of such settings interferes with the proper functioning of the driving mechanisms.

60 Mandrel 24 comprises three similar sectors as indicated in Fig. 10. Each sector is mounted upright on a section of the 3-jaw chuck 22. Chuck 22 is similar to the chuck 65 described in the above mentioned Patent

No. 1,155,389, and as the details of the chuck form no part of the present invention it is sufficient to say that when stem 80 (Fig. 3) is actuated with a wrench the chuck operates to move radially the three sectors of which 70 mandrel 24 is composed. If the sectors are moved inwardly, the diameter of the mandrel is decreased, while if they are moved outwardly the diameter is increased.

When the machine is in operation a tremendous inward radial thrust is exerted by the corrugating rollers, tending to crush the mandrel. In order to assist the mandrel to resist such forces, internal supports are provided at intervals, as for instance 82 and 84, 80 as shown in Figs. 3 and 10. 82 is a frustum of a cone and 84 a frustum of a triangular pyramid. 82 and 84 are tied together by rod 86. In operation, the shell 88 to be corrugated is dropped over the mandrel until it rests on pin 90. The mandrel is then expanded by means of chuck 22 until the mandrel snugly fits the shell. Wedges 82 and 84, due to their own weight and the pressure of coil spring 92, follow down into 90 their seats and remain there while the shell is being corrugated, serving to support the mandrel sectors against each other and thereby enabling them to resist bending or breaking. Hardened seats 94 and 96 are 95 provided for wedges 82 and 84 respectively. After the shell is corrugated, wedges 82 and 84 are found to be tightly held in position and require the exertion of considerable force to move them upwards into their non-operative positions, therefore an air cylinder 98 is provided, as indicated in Fig. 1, by means of which rod 100 is forced upwardly against the bottom of 84 to raise 82 and 84 100 from their seats and permit the collapsing 105 of the mandrel by means of chuck 22. Rod 100 passes through the hollow bore of shaft 20 and between the mandrel sectors (Fig. 3), in space provided for the purpose.

Projecting upwardly from the top of each 110 mandrel sector is a sector 102, the three sectors 102 forming a partly cylindrical and partly conical extension which projects into the socket 104 of spindle 106, which is provided to hold the upper end of the mandrel 115 central and steady while it is being rotated. Socket 104 is lined with hardened plates to reduce wear, and spindle 106 is supported for rotation in sleeve 108 by ball bearings 110 and 112 at its upper and lower ends respectively.

120 Spindle 106 and sleeve 108 are carried for operation in member 26 which is hinged by a ball bearing spindle 114 on head 12. Member 26 is hinged in order that it may be 125 swung to one side to permit passage of the shell through the semi-circular opening in head 12. While in operative position (Fig. 6) a hook-like projection 116 on the free end of member 26 engages one side of a slot 118 130

in head 12, thereby placing member 26 in tension from pin 114 to hook 116 while the machine is operating and thereby reinforcing head 12 against breakage. Further details of member 26 will be found in Fig. 5. Sleeve 108 and spindle 106 are raised and lowered by air cylinder 120. The flow of air to the upper and lower ends of cylinder 120 is controlled by valve 122 which is manipulated by handle 124. When air is admitted to the upper end of the cylinder, spindle 106 is forced down into engagement with hub 102, and held there. When air is admitted to the lower end of cylinder 120, piston 126 is forced upwardly thereby raising spindle 106 free of hub 102. Cylinder 128 and its piston 130 are provided simply to prevent escape of air around piston rod 132 when air is admitted below piston 126.

When air is admitted to the top of cylinder 120 it is also admitted through pipe 134 to vertical cylinder 136 in the free end of member 26. Cylinder 136 is provided with two pistons so arranged that when air is admitted between them one piston is forced upwardly and the other downwardly. Each piston is provided with a plunger 140, the outer conical ends of which normally engage conical seats 142 in head 12. So long as pressure is maintained in cylinder 136, plungers 140 will engage seats 142 and hold member 26 in operative position. When pressure in 136 is relieved, springs 138 will force plungers 140 inwardly, unlatching member 26 from head 12 so that 26 is free to swing on hinge pin 114.

The corrugating devices will now be described.

Mounted on each feed screw 46 is a split nut 144 to which is attached a box-like frame 18 extending inwardly from screw 46 towards mandrel 24. Screw 46 and mandrel 24 are rotated at such speeds relatively to each other that the corrugating device is kept in proper relationship to the screw threads on the surface of the mandrel. Slidably mounted in frame 18 is a box-like member 146 within which is rotatably mounted the corrugating wheel 148, which is shown with two circumferential recesses or rings, corresponding to the double threads on the mandrel. Wheel 148 is mounted for rotation on an axis 149 fixed in a member 151 which may be set at varying angles in member 146 in order to provide for any angle of thread on the shell. Screws 153, passing through slots 155 in the flange of member 151, serve to hold the member at the proper angle (Fig. 7).

In order to advance or retract wheel 148, air cylinders 150 are provided (Figs. 3 and 9), there being one cylinder 150 on each side of member 146, and connected thereto by piston rod 152 and trunnion 154 fast in outwardly projecting rib 156 of member 146.

The rear end of rib 156 is provided with a beveled surface 158, and with that surface is engaged a wedge 160 carried on the upper end of piston rod 162, which in turn is connected at its lower end to a piston 163 (Fig. 7) in the double acting air cylinder 164. In operation, air cylinders 150 force wheels 148 against the shell, pressing the metal thereof into the corrugations of the mandrel, then cylinders 164 draw wedges 160 into position to hold the wheels in the advanced position into which cylinders 150 placed them. To retract the wheels from the shell, cylinders 164 first withdraw wedges 160 and then cylinders 150 withdraw the wheels. The operation of cylinders 150 is controlled by hand lever 166 through valve 168, while cylinders 150 are controlled by lever 170 through valve 172, air for all cylinders being supplied through a hose connected to pipe 174. The entire corrugating structure, described above, is guided on planed portions of members 16 by guides 176, fast to frame 18. The two corrugating wheels 148 are placed substantially opposite each other, as shown in Fig. 1, in order to obviate any bending strain on the mandrel. Screws 46 are so driven that the two corrugating devices travel up and down together.

Mandrel 24 and screw 46 are made of reduced diameters and unthreaded near their lower ends at 178 and 180 (Figs. 1 and 2) respectively, so that in case the operator fails to stop the machine in time, wheels 148 and nuts 144 will run onto the unthreaded sections and stop, thereby preventing damage which might result if the threads were to extend further down.

Ring 182 rests loosely in recess 184 cut in the tops of the mandrel sectors (Fig. 3). This is a safety device which prevents the upper ends of the sectors flying out due to centrifugal force in case the machine should accidentally be started before spindle 106 was lowered to operative position.

Now that the entire machine has been described, its method of operation will be readily understood. The position of guide members 16 is first adjusted to suit the diameter and taper of the shell to be corrugated. Then lever 124 is moved to the position which releases air from cylinder 136 and from the upper end of cylinder 120, at the same time admitting air below piston 126. This raises spindle 106 from engagement with mandrel 24 and allows springs 138 to unlatch plungers 140. Member 26 is then swung to one side and a shell is lowered through head 12 onto mandrel 24 until it rests on pin 90. Chuck 22 is then adjusted by stem 80 until the mandrel sectors fit snugly against the inside of the shell. Wedges 82 and 84 assume their operative positions due to gravity and spring 92.

Member 26 is swung to operative position and lever 124 is moved, thereby admitting air above piston 126 and into 136, at the same time releasing air from below piston 126. 5 The air above piston 126 forces spindle 106 into engagement with hub 102, and the air in cylinder 136 forces plungers 140 into sockets 142.

Corrugating wheels 148 having been 10 brought to the top of the shell are forced inwardly by air cylinders 150 and there locked by wedges 160 actuated by cylinders 164.

The machine is then operated by power 15 supplied through shaft 28, rotating the mandrel and feed screws and causing the corrugating wheels to travel downwardly, forcing the shell into the corrugations of the mandrel and causing it to assume a permanent 20 shape conforming to the corrugations of the mandrel. When the bottom of the shell is reached by the corrugated wheels the machine is stopped, cylinders 164 and 150 are actuated to withdraw the wheels 25 from contact with the shell, and chuck 22 is operated to contract the mandrel, wedges 82 and 84 having first been raised by air cylinder 98 through the agency of rod 100.

Lever 124 is manipulated to operate pistons 126 and 138 to release member 26, which is then swung to one side to leave a free path for the removal of the shell through the head. Although the mandrel has been collapsed, its diameter is still too 35 great to permit lifting the shell directly off the mandrel, therefore the shell must be unscrewed from the mandrel. In the case of tapered shells it is sufficient to unscrew only a few turns, after which the shell may be 40 lifted off the mandrel by the overhead lifting tackle, not shown.

The unscrewing operation is accomplished by holding the shell against rotation and by reversing the direction of rotation of the 45 mandrel. A convenient device for preventing retrograde rotation of the shell during the unscrewing operation comprises the arms 186, one of which is pivoted at 188 on top of each corrugating device frame 18. When 50 the shell is to be held against retrograde rotation, these devices are swung over until their free ends 190, which are shod with rubber or leather, rest against the shell, in which position they permit upward and prevent 55 downward motion of the shell. The reversed motion of the unscrewing operation runs the corrugating wheels to the top of the machine, in position to begin on the next shell, when it is placed in position as already described.

60 The entire operation of the machine is very rapid, some of the above described manipulative operations taking place simultaneously, and the use of the air cylinders enables all operations to be carried out rapidly and 65 positively.

It is to be understood that the invention is not limited to the construction herein specifically illustrated but can be embodied in other forms without departing from its spirit. 70

I claim—

1. In a machine of the class described, in combination, a mandrel comprising a plurality of sectors, a chuck supporting the said sectors for radial outward movement, a device operating automatically at a point removed from said chuck to lock said sectors in said outward position for the purpose set forth, and manipulative means for disabling said locking device, said means including a fluid-pressure cylinder. 75 80

2. In a machine of the class described, in combination, a mandrel comprising a plurality of sectors, a chuck supporting the said sectors for radial outward movement, a device operating automatically at a point removed from said chuck to lock said sectors in said outward position for the purpose set forth, and manipulative means for disabling said locking device, said means including a fluid-pressure cylinder and a push rod operated thereby, said rod being located between and guided by said mandrel sectors. 85 90

3. In a machine of the class described, in combination, a mandrel comprising a plurality of sectors, a chuck supporting said sectors at one end thereof for radial outward movement, a device normally effective to limit the radial outward movement of the sectors at the end removed from said chuck, means for rotating said mandrel, and a safety device for automatically limiting the outward movement of the last-mentioned ends of said sectors if said mandrel should be rotated when said normal limiting device 105 is not effective. 95 100

4. In a machine of the class described, in combination, a mandrel comprising a plurality of sectors, a chuck supporting said sectors at one end thereof for radial outward movement, a device normally effective to limit the radial outward movement of the sectors at the end removed from said chuck, means for rotating said mandrel, and a safety device for automatically limiting the outward movement of the last-mentioned ends of said sectors if said mandrel should be rotated when said normal limiting device is not effective, said safety device comprising a ring-shaped member arranged 115 120 to engage all said mandrel sectors and restrain them against outward movement appreciably beyond normal position. 125

5. In a machine of the class described, in combination, a screw-corrugated mandrel, means for rotating said mandrel, a wheel having a rim so shaped as to fit the screw corrugation in said mandrel, means for feeding said wheel to keep it in contact with said screw corrugation while said mandrel 130

is rotating, and manipulative means including a fluid device for forcibly advancing said wheel towards said mandrel.

6. In a machine of the class described, in combination, a screw-corrugated mandrel, means for rotating said mandrel, a wheel having a rim so shaped as to fit the screw corrugation in said mandrel, means for feeding said wheel to keep it in contact with said screw corrugation while said mandrel is rotating, manipulative means for forcibly advancing said wheel towards said mandrel, and a locking device aside from said advancing device for holding said wheel in advanced position.

7. The invention set forth in claim 6, in which said locking device is manually controlled by means including a fluid-pressure device.

8. In a machine of the class described, in combination, a screw-corrugated mandrel, means for rotating said mandrel, two wheels having rims shaped to fit the screw corrugation in said mandrel, means for supporting said wheels for operation at points substantially diametrically opposite on said mandrel, means for feeding said wheels to keep them in contact with said screw corrugation while said mandrel is rotating, and manipulative devices for forcibly advancing said wheels towards said mandrel.

9. The invention set forth in claim 8, in which locking devices aside from said advancing devices are provided for holding said wheels in advanced positions.

10. The invention set forth in claim 8, in which locking devices aside from said advancing devices are provided for holding said wheels in advanced positions and in which manipulative devices including fluid-pressure actuated plungers are provided for operating said advancing and said locking devices.

11. In a machine of the class described, in combination, a mandrel, means for rotating said mandrel, means including a chuck for supporting one end of said mandrel, means including a spindle for engaging and supporting the other end of said mandrel, and manipulative means including a fluid-actuated plunger for forcing said spindle into or out of engagement with said mandrel.

12. In a machine of the class described, in combination, a mandrel, means for rotating said mandrel, means including a chuck for supporting one end of said mandrel, means including a spindle for engaging and supporting the other end of said mandrel, a movable member supporting said spindle in operative and non-operative positions, and a fluid-operated device to lock said movable member in operative position.

13. In a machine of the class described, in combination, a mandrel, means for rotating

said mandrel, means including a chuck for supporting one end of said mandrel, means including a spindle for engaging and supporting the other end of said mandrel, manipulative means including a fluid-controlled device for forcing said spindle into engagement with said mandrel, a movable member supporting said spindle in operative or non-operative position, a fluid-controlled device to lock said movable member in operative position, and means causing said fluid-controlled devices to operate simultaneously.

14. In a machine of the class described, in combination, a mandrel, means for rotating said mandrel, means including a chuck for supporting one end of said mandrel, means including a spindle for engaging and supporting the other end of said mandrel, manipulative means including a fluid-controlled device for drawing said spindle out of engagement with said mandrel, a movable member supporting said spindle in operative or non-operative position, a fluid-controlled device to unlock said movable member from operative position, and means causing said fluid-controlled devices to operate simultaneously.

15. In a machine of the class described, in combination, a mandrel, means for permanently supporting said mandrel at one end thereof, a device for intermittently supporting said mandrel at the other end thereof, said device having effective and ineffective operating positions, means for locking said device in effective position, and means independent of said locking means for absorbing the strains developed in and through said device due to operation of the machine.

16. In a machine of the class described, in combination, a mandrel supported for rotation, devices arranged for operation along the length of said mandrel parallel to the surface thereof, and means for rotating said mandrel and operating said devices in synchronism, said means comprising a shaft alined with the axis of said mandrel, a screw for actuating each of said devices, a shaft extending radially from said axially alined shaft towards each of said screws, means for driving all said radial shafts from a single gear on said axially alined shaft, and means for driving one of said screws from each of said radial shafts.

17. The invention set forth in claim 16, in which means is provided for varying the angle between each of said radial shafts and its corresponding screw.

18. The invention set forth in claim 16, in which the means for driving each of said screws from its radial shaft comprises a bevel gear on said shaft, a second bevel gear driven thereby, and a bevel gear on said screw driven by said second gear.

19. In a machine of the class described,

in combination, a mandrel supported for rotation, devices arranged for operation along the length of said mandrel parallel to the surface thereof; means for rotating said mandrel and operating said devices in synchronism, said means comprising a shaft on the axis of said mandrel, a screw for actuating each of said devices, a shaft extending radially from said axial shaft to intersect the axis of each of said screws, means for driving all said radial shafts from a single gear on said axial shaft, and means for driving one of said screws from each of said radial shafts; means for varying the angle between each of said radial shafts and its corresponding screw, said means including a pivotal support for said screw, the axis of said pivotal support intersecting at right angles the axes of said screw and said shaft, and the means for driving each of said screws from its radial shaft comprising a bevel gear on said shaft, a second bevel gear driven thereby, and a bevel gear on said screw and driven by said second gear, the axis of rotation of said second gear coinciding with the axis of the pivotal support of said screw.

20. In a shell corrugating machine, in combination, a mandrel on which the shell to be corrugated is placed, mechanism for corrugating the shell while it is on said mandrel, means for removing the shell from said mandrel after the shell is corrugated, and a device settable to automatically prevent retrograde movement of the shell during the removing operation.

21. In a shell corrugating machine, in combination, a screw-threaded mandrel on which the shell is placed to be corrugated, mechanism for forming screw-threaded corrugation on the shell while the shell is on said mandrel, means for unscrewing the shell from said mandrel after it is corrugated, and a device settable to automatically prevent retrograde movement of the shell during the removing operation.

22. The invention set forth in claim 20, in which said device comprises a shoe arranged to frictionally engage the surface of the shell for the purpose set forth.

In testimony whereof I hereto affix my signature.

FREDERICK A. SCHROEDER.
